[57] CLAIM

We claim the ornamental design for a toy brick bottle, as shown and described.

DESCRIPTION

FIG. 1 is a bottom, right, front perspective view of a toy brick bottle showing our new design;

FIG. 2 is a top, right rear perspective view thereof;

FIG. 3 is a bottom plan view thereof;

FIG. 4 is a top plan view thereof;

FIG. 5 is a bottom, right, front perspective view of a second embodiment of FIG. 1;

FIG. 6 is a top, right, rear perspective view of FIG. 5;

FIG. 7 is a bottom plan view of FIG. 5; and,

FIG. 8 is a top plan view of FIG. 5.
